UNITED STATES PATENT OFFICE.

HENRY L. DOHERTY, OF NEW YORK, N. Y.

METHOD OF AND APPARATUS FOR REFRIGERATION.

Application filed July 7, 1920. Serial No. 394,491.

To all whom it may concern:

Be it known that I, HENRY L. DOHERTY, a citizen of the United States of America, residing at New York city, in the county of 5 New York, State of New York, have invented certain new and useful Improvements in Methods of and Apparatus for Refrigeration; and I do hereby declare the following to be a full, clear, and exact description of the invention, such as will enable others skilled in the art to which it appertains to make and use the same.

This invention relates to a method of and an apparatus for refrigeration, and more 15 specifically to a method and apparatus in which heat is abstracted from a space to be cooled and the heat is in turn transferred to a body to be heated.

Low temperatures for refrigeration purposes may be obtained by two methods, one 20 of which is to place a mass of ice in the space to be cooled, and the other method is to abstract the heat from the space to be cooled by mechanical and thermodynamic means.

25 The first method has been the more widely used for domestic or household refrigeration because of its simplicity, but it has several disadvantages as compared with the second method. Among these disadvan-

30 tages is the necessity for replacing the melted ice at frequent intervals and the danger, where the supply is irregular, or where the quantity necessary for a certain period of time is uncertain, that one charge of ice may

35 not last until a fresh supply is received and that the foods placed in the refrigerator may deteriorate or spoil in the interval. Added to these disadvantages there is a further disadvantage that the temperature of the re-

40 frigerator is of necessity limited by the melting point of the ice and cannot be varied or controlled to give the best temperature and humidity conditions for the preservation of food.

45 Mechanical or artificial methods of refrigeration do not suffer from these defects, since the supply of energy for refrigeration may be made continuous and automatic and the temperature produced is independent of any fixed points. Refrigeration by the second method is also cheaper because of the comparatively lower cost of the energy used. Thus, one pound of ice absorbs 50 only about 144 B. t. u. in melting whereas the combustion of one cubic foot of gas

yields energy equivalent to about 600 B. t. u. Since the cost of a cubic foot of gas is but a fraction of the cost of a pound of ice, it is therefore evident that it would be much cheaper to use energy obtained by the combustion of gas even though a very small efficiency were obtained in the application of this energy for refrigeration purposes. Where fuel is also used for heating or other purposes, refrigeration may be obtained without the use of additional fuel, by applying a part of the energy of combustion to abstract heat from the refrigerator and applying the heat returned by the refrigerating operation for heating water or for other 70 heating purposes. With such an arrangement, refrigeration may be obtained with very little, if any, expense over the cost of the heating operation alone, since there is a gain rather than a loss of heat to the system 75 from the refrigerating operation.

The type of refrigerating machines used in storage warehouses and other large scale refrigerating plants are, however, not suitable for adaptation to domestic or household purposes, because they are cumbersome and require constant attention and a certain amount of engineering skill in their operation. A refrigerating plant suitable for small sized, or household, purposes must be simple in construction and require little or no attention in daily operation. It should be so arranged that upon supplying power or fuel the apparatus will be automatically set in operation and will continue to operate 80 without further attention. To this end all moving parts requiring packing or lubrication must be avoided and the whole apparatus should be self-contained and independent of outside conditions.

95 The primary object of the present invention is to provide a method of refrigeration in which energy is applied to produce a refrigerating effect and the heat given up by the refrigerating operation is applied to 100 produce useful heating effects.

Another object of the invention is to provide a refrigerating apparatus in which energy is applied to produce a refrigerating effect and the heat given up in the refrigerating operation is used to produce useful 105 heating effects.

Another object of the present invention is to provide a simple and compact refrigerating apparatus for domestic purposes.

A further object of the invention is to provide a refrigerating apparatus for domestic purposes which will be automatic in its operations, such as in the regulation of the cooling temperature, of the heating temperature, the refrigeration temperature and the safety control for the fuel gas supply.

With these and other objects in view, the invention consists in the method and apparatus described in the following specification and defined in the claims.

The various features of the invention are shown in the accompanying drawings, in which:

15 Fig. 1 is an elevation partly in section, of a refrigerating apparatus embodying a preferred form of the invention;

Fig. 2 is a detailed sectional view of a pressure boiler or generator of the refrigerating apparatus for driving the ammonia gas out of solution.

20 Fig. 3 is a detailed sectional view of a hot water heater in which water is heated by the condensation of ammonia gas under pressure;

25 Fig. 4 is a detailed sectional view of an absorption chamber for ammonia gas and shows the lower portion of the water heater illustrated in Fig. 3;

30 Fig. 5 is a detailed sectional view of the ammonia expansion valve; and

Fig. 6 is a detailed sectional view of the gas supply regulating valve.

In the present invention the combustion of fuel gas is used as a source of energy for refrigeration and for heating water in a hot water supply system. For this purpose a saturated solution of ammonia gas is heated in a boiler capable of withstanding a high pressure and the ammonia is thereby driven out of solution. The ammonia gas driven out of solution by the heating is condensed under pressure to liquid ammonia. When a sufficient amount of ammonia has been driven out of solution and condensed, the residual liquor is removed from the boiler and cooled. The condensed ammonia is expanded through expansion and refrigeration coils placed in the medium to be cooled, is thereby reduced in temperature and cools the medium by the abstraction of heat therefrom. The expanded ammonia is then reabsorbed in the cooled ammonia liquor and is returned with the liquor to the pressure boiler or generator and the cycle of operations is repeated.

60 The heat given off by the condensation of the ammonia gas, by the absorption of ammonia gas and in the cooling of the ammonia liquor is used to heat water in a hot water supply system in such a manner that the water is successively heated by fluids of increasingly higher temperature. In this manner, the heat of combustion supplied to the 65 generator by the gas flame is transferred to

the hot water heating system and an additional amount of heat absorbed by the cooled ammonia gas in passing through the refrigerating coils is also returned to the water heating system when the ammonia gas is redissolved in ammonia liquor.

In the illustrated embodiment of the invention shown in the drawings, a pressure boiler or generator 10 (Figs. 1 and 2) is heated by a gas flame from a burner 12 placed beneath the generator. The products of combustion from the burner 12 pass upwardly between the generator 10 and a surrounding mantel 14 and are exhausted from

the upper part of the mantel 14 through a chimney 16. The generator 10 is partly filled with a concentrated solution of ammonia in water, and as the boiler is heated, the ammonia is driven out of solution and rises through a vapor pipe 18 (Figs. 2 and 3) which has a comparatively large diameter to

80 permit entrained water to drop back to the generator. From the upper end of the vapor pipe the ammonia gas passes through a check valve 20 (Fig. 3) into a cooling coil 22 en-

85 closed within a hot water heater 24. As additional quantities of ammonia gas are driven off, the pressure of the ammonia in the generator 10 and in the condensing coil

90 22 continually increases until it reaches a pressure of approximately 175 pounds per square inch. At this pressure, the ammonia condenses in the lower part of the coil 22 thereby raising the temperature of the water

95 surrounding the coil to approximately 85° F. As additional quantities of ammonia are driven from the generator 10 into the coil 22, the ammonia is cooled in passing through the upper part of the coil which is sur-

100 rounded by partly heated water and as it reaches the lower part of the coil it is cooled to a temperature at which it condenses and forms a body of liquid ammonia in the lower-

105 most part of the coil. The condensed ammonia is prevented from passing back into the generator 10 by the check valve 20. From the lower part of the coil 22 the liquid ammonia is withdrawn through a pipe 26 to an expansion chamber 28 of a thermostati-

110 cally controlled expansion valve 30. In the expansion chamber 28 the pressure on the liquid ammonia is released and the ammonia thereupon vaporizes and is cooled to a very low temperature. The cooled expanded am-

115 monia gas flows from the expansion chamber into a cooling coil 32 positioned within

120 a cooling chamber in a refrigerator 34. In passing through the coil 32, the ammonia cools the refrigerator and is itself heated by the abstraction of heat from the refrig-

125 erator. The extent to which the ammonia gas is heated by this operation and the resulting temperature of the gas depends upon

130 the temperature conditions in the refrigerator and is a measure of the amount of am-

monia required to maintain the desired temperature in the refrigerator. The ammonia gas leaving the coil 32 is, thereupon, passed into a thermostatic chamber 36 of the valve 5 28 in which it acts to control the passage of liquid ammonia through the valve. From the chamber 36 the gas passes through a return pipe 38 and liquid pipe 40 to an absorbing chamber 42 in the water heater 24, in 10 which it is reabsorbed in cool residual liquor and from which it is returned to the generator 10. The cycle is thereupon repeated.

As the ammonia liquor in the generator 10 is heated in driving out the dissolved ammonia gas it becomes continually weaker in ammonia and a higher temperature is required for driving out additional quantities of ammonia gas. When a temperature is reached at which a considerable amount of 20 water is vaporized with the ammonia, a thermostatically controlled valve 44 closing the end of a liquor draw-off pipe 46 extending into the generator 10 (Fig. 2) is opened and the liquor is forced into the draw-off 25 pipe by the gaseous pressure in the upper part of the generator. The liquor passes through the pipe 46 into a cooling coil 48 forming a continuation of the pipe 46 in the heater 24 and enters the absorption chamber 30 ber 42.

The opening of the valve 44 in the generator 10 is controlled by means of a thermostat 50, the lower end of which is connected by means of a rod 52 to the valve 44 and the 35 upper cap 54 of which is adjustably supported by a rod 56 extending from the cover 58 of the generator. The rod 56 is threaded in the cap 58 and its outer end 60 is squared so that the position of the rod 56 may be ad- 40 justed vertically by turning the squared portion 60, to vary the temperature at which the valve 44 opens. Accidental turning or tampering with the position of the rod is prevented by a removable cap 62 covering 45 the projecting end of the rod. The thermostat and rod are also protected from lateral movement within the generator 10 by a casting 64 having slots 66 to permit access of the liquor to the thermostat 50.

50 The liquor outlet pipe 46 and the cooling coil 48 have a small diameter to prevent a rapid flow of liquor and to give sufficient time for the liquor to be cooled while passing through the coil 48. When all of the liquor 55 has been transferred from the generator 10 to the absorption chamber 42, the pressures in the generator and absorption chamber tend to equalize by the passage of ammonia gas from the generator through the pipe 46, 60 and permit the liquor saturated with ammonia in the absorption chamber 42 to flow back by gravity into the generator.

Because of the small diameter of the pipe 65 46, the equalization of pressure between the generator 10 and the absorption chamber 42

through the pipe 46 is so slow that considerable time would be required for the return of all of the liquor from the absorption chamber 42 to the generator. As the first portions of returning saturated liquor come 70 into contact with the heated walls of the generator, there is an immediate generation of ammonia gas and building up of pressure which would prevent further inflow of liquor. To hasten the return of the cold saturated liquor to the generator 10, therefore, gas under pressure is by-passed from the pipe 18 to the absorbing chamber 42 through a by-pass pipe 68 (Figs. 1 and 4) and the cooled liquor is permitted to immediately fall 75 through the return pipe 40 which is of a comparatively large diameter.

The liquor is not admitted directly into the generator because of the sudden generation of pressure, but is led into an intermediate storage tank 70 which is of sufficient size to store all of the liquor and is in communication with the generator 10 through a liquor return pipe 72 and a pressure equalizing pipe 74. The diameters of the pipes 40, 80 72 and 74 are so proportioned that the liquor flows from the absorption chamber 42 to the storage chamber 70 in a very short time, but the pipe 72 leading from the storage tank to the generator, is of such a small diameter that 85 very little of the liquor will flow from the tank into the generator during the time of filling the tank 70. As the liquor flows from the tank 70 into the generator 10, a pressure is immediately built up which is transmitted 90 to the tank 70 through the pressure equalizing pipe 74, but the liquor in the tank is prevented from flowing back to the absorber 42 by means of a check valve 76 in the tank 70 (Fig. 2) closing the end of the pipe 40. The 95 pressure in the generator does not prevent the inflow of liquor from the tank 70 through the pipe 72, since this pressure is transmitted through the pressure equalizing pipe 74 to the surface of the liquor in the tank 70. 100

The by-passing of gas from the pipe 18 through the by-pass pipe 68 is controlled by a compound valve which is opened when the liquor in the absorption chamber 42 reaches a definite level and is maintained 105 in open position until the chamber is emptied of liquor. This valve comprises an outer shell 78 (Fig. 4) positioned in a valve chamber 80 in the top of the absorption chamber and is arranged to close an opening 79 between the absorption chamber and the valve chamber 80. The valve chamber 80 communicates with the by-pass pipe 68 through a series of lateral openings 84 in the top 85 of the valve chamber. The shell 110 78 is vertically movable in the valve chamber and is maintained in an upright position by means of a stem 86 sliding in a sleeve 88 depending from the top of the valve chamber. The lower end of the shell 115

78 is provided with an opening 90 which is in turn closed by a solid valve 92. The sides of the shell 78 are also provided with a series of openings 94 which transmit pressure from the valve chamber 80 and by-pass pipe 68 to the top of the solid valve 92. The valve 92 is provided with a downwardly extending stem 96 which is in turn rigidly connected through a hollow rod 98 to a float 100 in the lower part of the absorption chamber. As the absorption chamber 42 is filled and liquid submerges the float 100, the buoyant effect of the float exerts a lifting force on the valve 92 which is sufficient to support the weight of the valve, but is not sufficient to lift the valve against the pressure in the valve chamber 80 acting downwardly on the valve. As the level of the liquor in the absorption chamber rises, it submerges a second, larger float 102 loosely surrounding the rod 98 and vertically movable in relation thereto. As the liquor rises upwardly around the float 102 it lifts the float and compresses a spring 104 between a disc 106 on the upper face of the float and a disc 108 rigidly mounted on the rod 98. The spring 104 is compressed until the force of compression added to the buoyant force of the float 100 is sufficient to lift the valve 92. When this occurs, the spring 104 throws the valve 92 upwardly against the top of the shell 78 with sufficient force and momentum to lift the shell 78 from the valve seat opening 79. The pressure between the valve chamber 80 and the expansion chamber 42 is thereby immediately equalized and the valve held in its upper position. A rapid flow of gas from the pipe 18 through the by-pass pipe 68 and valve opening 79 is thereby permitted and the liquor rapidly falls by gravity through the outlet pipe 40 to the storage chamber 70. As the liquor falls below the float 102, the valve 92 and shell 78 are supported by the float 100, since there is no difference in pressure tending to overcome the buoyant effect of the float 100. At the time the liquor falls below the float 100, the valve 92 and shell 78 are closed by their own weight and the weight of the stem 98 and float 100.

The heat absorbed in the generator 10 is transferred and given up to the water in the heater 24 by the condensation of the ammonia in the condensing coil 22, the absorption of ammonia gas in the cool liquor in the absorber 42 and by the transference of heat from the hot liquor and gases in the coils 22 and 48 in the upper part of the heater 24. The temperature to which the water can be raised by the condensation of the ammonia gas in the coil 22 is limited to approximately 85° F. which is the condensation temperature of ammonia under a pressure of 165 pounds, which is the maxi-

mum pressure employed in the system. The absorption of ammonia gas by the cool liquor in the absorption chamber 42 is also an exothermic process which may be carried out at temperatures somewhat above 85° F. It is desirable, however, not to carry out the step of absorption at a very high temperature because the solubility of ammonia in the liquor decreases with the temperature, the rate of absorption is accordingly decreased and a weaker solution of ammonia is obtained. The temperature obtained by the transference of heat from the upper part of the coils 22 and 48 is, however, limited only by the temperature and thermal capacity of the hot liquor and gases. To obtain a temperature of the hot water suitable for domestic use, the water being heated is therefore heated first by the condensing ammonia, then by the absorption of ammonia in the cool liquor and finally by the transference of heat from the hot liquor and hot ammonia gases in the coils 22 and 48.

To this end, the water is drawn from a reservoir or stand boiler 110 through a circulating pipe 112, and branch pipe 114 to the bottom of the heater 24. The circulating water passes upwardly through the heater 24 being heated first by the condensing ammonia in the lower part of the coil 22 and still further heated by the heat given up in the absorption of ammonia in the chamber 42, and finally by the direct transfer of heat from the coils 48 in the upper part of the coil 22. The heated water leaves the upper part of the chamber 24 and returns to the stand boiler through a return pipe 116. The stand boiler is gradually filled with hot water which may be removed from the upper part of the boiler, through a draw-off pipe 118, a fresh supply being introduced into the lower part of the boiler by the inlet pipe 120. The stand boiler may be also connected to other heating means through the branch pipe 122 when the refrigerator is not in operation.

Since the vapor pressure of ammonia gas rises very rapidly with small increases in temperature above 85° F., the temperature in the heater 24 should be so controlled that the lower portion of the heater will not rise above approximately 85° F. The heater is therefore provided at its upper end with a temperature controlled release valve 124 shown in detail in Fig. 3 which opens the heater into direct communication with a waste pipe 126 when the temperature rises above a definite limit. The temperature of the water is measured by an expansion thermostat 128, the lower end of which is rigidly held in an enclosing case 130 suspended from a depending flange 132 on the top of the heater 24. The case 130 is provided with openings 134 and 136 at its lower and up-

per ends respectively, to permit a rapid circulation of hot water around the thermostat 128. The upper end of the thermostat is free to move in a vertical direction as the thermostat expands and contracts and imparts its motion through a valve stem 140 to a valve 142. When the temperature of the thermostat is below a definite safe limit, the valve 142 is pressed downwardly onto the valve seat 144 by means of a spring 146, placed between the upper face of the valve and a vertically adjustable plate 148. When the temperature of the water rises above a definite limit, the expansion of the thermostat 128 lifts the valve 142 from its seat against the action of the spring 146 and permits the water to flow through openings 150 in the flange 132, through the valve seat opening 144, and the openings 152 in the valve 142 to the waste pipe 126. A fresh supply of cool water is thereupon drawn through the pipe 120 to the bottom of the stand boiler 110 and flows through the pipes 112 and 114 to the lower portion of the heater 24, thereby cooling the lower portion of the heater. The pressure exerted by the spring 146 on the valve 142 may be adjusted by means of three adjusting screws 154 acting on the plate 148. The valve stem 140 is threaded on the valve 142 and the position of the thermostat top 138 and the valve 142 may be adjusted by rotating the valve stem 140 by means of a rotatable screw 156, slidably connected with the rod 140.

The temperature in the refrigerator 34 is also maintained within definite limits by means of a thermostat 158 in the chamber 36 of the valve 28, as shown in detail in Fig. 5. The upper end 160 of the thermostat is fixedly supported by a yoke 162 which is in turn supported by a rod 164 threaded at 166 in the bottom of the chamber 36. The end of the rod 164 extending through the bottom of the chamber 36 is squared at 168 to permit the rod to be turned and adjusted in a vertical position. The lower end 170 of the thermostat is connected by means of a yoke 172 to a valve stem 174 extending into the expansion chamber 30 of the valve, and controls the admission of liquid ammonia from the pipe 26 to the chamber 30. The liquid ammonia entering the valve 28 through the pipe 26 is received in a small valve chamber 176 formed in the upper part of the chamber 30 and closed at its lower end by a plate 178. The plate 178 is provided with a small opening 180 forming a valve seat for the valve member 174. When the temperature of the refrigerator rises above the maximum limit, the exhaust ammonia gas delivered to the chamber 36 through the coils 32 causes the thermostat 158 to expand and move the lower end 170 of the thermostat downwardly. This downward movement is transmitted through the yoke 172 to the

valve 174 and the valve is drawn away from the opening 180 permitting the liquid ammonia to flow freely from the valve chamber 176 to the expansion chamber 30 and the cooling coils 32. As the temperature of the refrigerator falls below a definite limit, the waste gases delivered to the chamber 36 from the coils 32 become cooler and cause the thermostat 158 to contract. The lower end 170 of the thermostat is thereupon drawn upwardly and forces the valve 174 to contact with the valve opening 180 to close or partly close the opening 180 and stop or nearly stop the inflow of liquid ammonia. The temperature limits at which the valve 174 is moved can be adjusted by turning the squared end 168 of the thermostat support rod 164. Accidental turning or tampering with the rod 168 is however prevented by means of a cap 182 covering the end of the rod. The flow of ammonia may also be limited or controlled independently of the valve 174 by a needle valve 184 having a threaded portion 186 extending through a top 188 of the expansion chamber 30. The upper end of the rod 184 is squared at 190 to permit the rod to be turned and the projecting end of the rod is enclosed in a cap 192.

In case any of the valves should fail to function properly or in case any part of the apparatus should become clogged or stopped, a dangerous pressure might be built up in the system if the heating of the generator 10 were continued. A valve device is therefore provided to shut off the supply of gas to the burner 12 and to thereby stop the operation of the apparatus when the pressure of ammonia in the system increases beyond a certain point. To this end, the gas for the burner 12 is led from a main 194 through a pressure safety device 196 to a pipe 198 leading directly to the burner 12 (Figs. 1 and 6). The safety device is divided into a high pressure chamber 200, which communicates with the ammonia condensing coil 22 through a connecting pipe 202, and a gas compartment 204 through which gas flows to the burner supply pipe 198. The supply of gas from the main 194 to the gas chamber 204 is regulated by a valve 206, the position of which is controlled by the pressure in the high pressure chamber 200. The valve 206 is arranged to close an opening 208 connecting the gas chamber 204 with a gas inlet compartment 210 formed in a cap 212 closing the upper part of the gas chamber 204. The valve 206 is mounted on a valve stem 214 and is ordinarily held in open position by a spring 216 which is confined between the closing cap 212 of the chamber 204 and a disk 218 which is threaded on the stem 214. The spring 216 tends to force the disk 218 downwardly and to thereby carry the stem 214

and the valve 206 downwardly into open position. However, when the pressure within the chamber 200 increases beyond a certain definite point, the valve stem 214 and disk 218 are moved upwardly against the action of the spring 216 and lift the valve 206 upward to close the opening 208.

Because of the high pressure normally existing in the chamber 200 and the necessity of absolutely preventing any escape of the ammonia from the chamber 200 into the chamber 204, packing devices can not be relied on for preventing the escape of gas around the elements through which movement is transmitted from the chamber 200 to the valve 206. To avoid any possibility of an escape of gas from the chamber 200, a device which forms a hermetic seal between the chambers 200 and 204 is employed. The hermetic sealing device consists of a corrugated tube 220 hermetically attached at its upper end to a partition 222 dividing the chambers 200 and 204 and hermetically closed at its lower end by a movable bulb 224. The valve stem 214 is extended downwardly through an opening 226 in the partition 222 until it reaches the movable plug 224. The action of the spring 216 transmitted through the disk 218 and valve stem 214 forces the plug 224 downwardly to its lowermost position. When a pressure is built up in the pressure chamber 200, the action of the spring 216 is opposed, the corrugated tube is compressed and the plug 224 is lifted upwardly against the action of the spring 216. The tension of the spring is so adjusted that when the pressure in the condensing coil 22, and accordingly in the pressure chamber 200, is increased beyond a certain limit, the pressure of the gas will force the supply of gas to the burner 12. The tension on the spring 216 and accordingly the pressure at which the valve 204 will be opened, is adjusted by rotating the valve stem 214 on the disk 218 and valve 206. For this purpose the gas compartment 210 is closed by means of a removable cap 228. To adjust the position of the valve 206 and disk 218 on the valve stem 214, the cap 228 is removed and the valve stem 214 is rotated by means of a screw driver inserted through the opening in the top of the compartment 210. A small bleed or pilot passage 230 is provided in the cap 212 through which a small amount of gas will be allowed to pass when the valve 204 is in fully closed position to guard against the escape of unburned gases due to successive closing and opening of the valve 204. The rate at which gas may pass through the pilot passage 230 is controlled by a needle valve 232.

By means of the method and apparatus described above all of the heat energy absorbed by the generator 10 from the flame

of the burner 12 is transmitted to the hot water heater 24. The efficiency of the heater 24, considered purely from the hot water heating standpoint, is equal to the efficiency of the generator 10 and is not decreased in any way by the refrigerating operation. In fact, some heat is absorbed from the refrigerator 34, carried to the hot water heater 24 and added to the heat which is introduced to the heater 24 from the generator 10. This additional amount of heat is not obtained as a result of a loss of any heat given up to the generator 10, but is obtained by a transfer of heat from the comparatively colder refrigerator to the comparatively warmer hot water heater brought about through a drop in temperature, and correspondingly a drop in the potential of the available energy imparted to the generator 10 from the gas flame of the burner 12. By taking advantage of the different temperatures at which the operations of condensing and absorbing ammonia and of cooling the ammonia liquor are carried on, the apparatus is arranged to heat the water passing from the hot water heater 24 to a much higher temperature than would be possible if but a single operation were relied upon for this purpose, and to thereby combine a high efficiency of operation with a maximum temperature obtained in the heating of water.

Having described the invention, what is claimed as new is:

1. A method of heating water and producing refrigeration, which comprises distilling ammonia gas from an ammonia solution under pressure by the application of heat, condensing under the said pressure the ammonia gas through heat interchange with a body of water to be heated, circulating the said body of water to a chamber from which it may be withdrawn for domestic use, regulating the heating of the ammonia solution in accordance with variations in pressure of the ammonia gas undergoing distillation, automatically transferring the hot residual ammonia solution into heat transferring relationship with the said body of water when the said solution reaches a definite predetermined temperature and thereby cooling the solution, automatically withdrawing a portion of the said body of water when the temperature thereof exceeds a predetermined value, and delivering cooled water thereto, thereby maintaining controllable temperature conditions for the condensation of the ammonia gas, vaporizing the liquefied ammonia gas under reduced pressure in heat transferring relation to a body of refrigerating fluid, and automatically controlling the vaporization thereof in accordance with the temperature of the ammonia gas passing out of the said heat transferring relationship, absorbing the gas

thereafter in the cooled residual ammonia solution, and returning the resulting solution to the original zone to be redistilled.

2. An apparatus for refrigerating and for heating water comprising a stand boiler and circulating water heater, a heating generator for driving ammonia gas out of an ammonia solution under pressure, a condenser in said circulating water heater for condensing said ammonia gas under pressure and heating water in said circulating heater, means for automatically removing the entire body of exhausted ammonia liquor from the heating generator at one time, means for cooling said exhaust liquor comprising a single container, means for expanding the condensed ammonia gas in heat absorbing relation for refrigeration, means for absorbing the expanded ammonia gas in said cooled ammonia liquor, and means for returning ammonia solution to said generator.

3. An apparatus for refrigerating and for heating water, comprising a water storage tank, a circulating water heater connected to said tank, a pressure boiler, a vapor pipe leading from the top of said boiler through said water heater and forming a condensing coil therein, a check valve in said vapor pipe, a waste liquor pipe leading from the bottom of said pressure boiler through said heater and forming a coil in said heater, an absorbing chamber in said water heater below the coil in said liquor pipe and into which said liquor pipe delivers, an expansion and cooling coil, a pressure reducing valve connecting said vapor pipe to said expansion coil, a return pipe from said cooling coil to said absorbing chamber, a by-pass from said vapor pipe to said absorption chamber, a float controlled valve in said absorption chamber controlling the by-passing of ammonia to said absorption chamber, a return pipe from said absorption chamber to said pressure boiler, and a check valve in said return pipe.

4. An apparatus for refrigerating and for heating water, comprising a hot water storage tank, a circulating water heater connected to said tank, a pressure boiler, a vapor pipe leading from the top of said pressure boiler thru said circulating water heater, an exhaust liquor pipe leading from the bottom of said pressure boiler into said circulating water heater and forming a coil in the heater, an absorption chamber in said water heater below the coil in said liquor pipe and into which said liquor pipe delivers, a thermostatically controlled valve in said pressure boiler governing the entrance of said exhaust liquor pipe, a check valve in said vapor pipe, an expansion coil, a differential pressure valve connecting said

vapor pipe to said expansion coil, and a return pipe leading from said expansion coil to said absorption chamber, a return pipe from said absorption chamber to said pressure boiler, and a check valve in said return pipe.

5. A combination refrigerator and hot water heater which comprises a generator for driving ammonia out of solution under pressure, a water heater, a cooling and condensing coil in said water heater arranged to receive and condense ammonia gas from said generator, a liquor cooling coil in said water heater, means for automatically transferring liquor from said generator, to said liquor cooling coil when the liquor in said generator reaches a definite temperature, an absorption chamber in said water heater connected to one end of said liquor cooling coil, a thermostatically controlled valve governing the end of said ammonia condensing coil and having a thermostat chamber connected to said absorption chamber, an ammonia expansion coil connected through said thermostatically controlled valve to said ammonia condensing coil, and means for returning ammonia liquor from said absorption chamber to said generator when the pressures in the absorption chamber and generator have become equalized, said means comprising a pipe, containing a check valve seated by pressure on the generator side thereof, a tank between said check valve and generator, and a liquor connection and a pressure equalizing connection between said tank and said generator.

6. A combination refrigerator and hot water heater comprising a generator for heating and driving ammonia out of an ammonia solution, a hot water heater, an ammonia condensing coil leading from said generator and extending through said hot water heater, an ammonia absorber in said hot water heater, a cooling coil in said hot water heater outside of said absorber, said cooling coil being connected at one end to said generator and at the other end to said absorber, automatic means for expanding ammonia from said condensing coil to produce refrigeration thereby, automatic means for transferring weak ammonia liquor from said generator to said absorber through said cooling coil, connections for leading ammonia gas from said expanding means to said absorber, automatic means whereby strong ammonia liquor is returned from said absorber to said generator, and automatic means for regulating the heating of said generator in accordance with variations in pressure of the ammonia gas intermediate said generator and said expanding means.

In testimony whereof I affix my signature.

HENRY L. DOHERTY.
